Primary Examiner — Darlington Ly*(74) Attorney, Agent, or Firm* — FisherBroyles LLP;
 Micah D. Stolowitz**CLAIM**

The ornamental design for a sport bottle, as shown and described.

DESCRIPTION

FIG. 1 is a perspective view of a sport bottle showing our new design;

FIG. 2 is a left side elevation view thereof;

FIG. 3 is a front elevation view thereof;

FIG. 4 is a right side elevation view thereof;

FIG. 5 is a rear elevation view thereof;

FIG. 6 is a top plan view thereof;

FIG. 7 is a bottom plan view thereof;

FIG. 8 is a perspective view thereof, showing the lid in a first use condition; and,

FIG. 9 is a perspective view thereof, [in another] showing the lid in a second use condition.

The broken lines in the drawings illustrate portions of the sport bottle that form no part of the claimed design.

1 Claim, 5 Drawing Sheets

Matter enclosed in heavy brackets [ ] appears in the original patent but forms no part of this reissue; matter printed in italics indicates the additions made by reissue.
